UNITED STATES PATENT OFFICE.

ROBERT W. CORNWALL, OF CLEVELAND, OHIO.

BEAM OR DRUM.

1,372,484.

Specification of Letters Patent. Patented Mar. 22, 1921.

Application filed March 17, 1919. Serial No. 283,122.

To all whom it may concern:

Be it known that I, ROBERT W. CORNWALL, a citizen of the United States, residing at Cleveland, in the county of Cuyahoga and State of Ohio, have invented certain new and useful Improvements in Beams or Drums, of which the following is a specification.

This invention relates to beams or drums for receiving webs of material and particularly to that class of such devices utilized for supporting fabrics used in the manufacture of tires.

In the manufacture of tires a vast quantity of fabric is utilized. Some of this fabric is substantially seventy-two inches in width and is wound upon a beam or drum which is placed in a suitable apparatus provided with a square shaft for receiving this beam or drum. In this apparatus there is a drag created by the mechanism which causes the inner convolution of fabric to hug the shell or periphery of the beam or drum and through friction to tend to produce such a torque on this shell with respect to its inner mechanism and the square shaft that in many instances the rivets employed in the usual form of beam or drum are sheared. In other words, in the ordinary construction there is a tendency at all times for the shell to shear off its connections with the inner structure and this tendency is so great when rivets are used that they are actually sheared. This is overcome in the present device by employing an inner structure of a type such that the shearing torque of the shell is borne by an inwardly turned flange which has ample bearing against the heads and webs of the inner structure and thereby relieves the rivets.

The invention will more fully and at large appear in the following description, drawings and claims.

Referring to the drawings, Figure 1 is a foreshortened view partly in elevation and partly in section showing the beam or drum; Fig. 2 is an end elevation; and Fig. 3 is a section upon the line 3—3, of Fig. 1.

The beam is made up of two heads identical in form, intermediate webs, an outer shell and an inner shell, the heads being identical in form and the webs being identical in form so that a description of one of the heads and one of the webs will suffice for both in each case.

The inner shell or hub of the beam or

drum comprises a pair of right angle members 1 and 2, each having along its edges flanges 3 which are adapted in the assembled arrangement to engage back to back as shown in Figs. 2 and 3. The beam or drum is provided with a pair of heads each consisting of a main head portion 4 having an outwardly extending peripheral flange 5 shown in dotted lines, Fig. 1. This flange and a portion of the main head portion 4 are provided with diametrically opposed inwardly extending slots 6 for a purpose to be described. The main head portion 4 is provided with a hub portion 7 having a square opening 8 therein as clearly shown in Fig. 2 for the reception of the inner shell or tubular hub comprising the members 1 and 2. Suitable slots 9 are provided at opposed corners of the square openings in this main head portion 4 to receive the flanges 3 as clearly shown in said figure. In order to hold the inner shell or tubular hub in place between the heads, each of the latter is provided with an inwardly extending flange 10 as shown in Fig. 1. Each head hub portion is further provided with a conical extension 11 extending inwardly and provided with a cylindrical flange 12 shown in dotted lines in Fig. 1. This conical extension and the flanges 12 are provided with slots 11' aligning with the slots 6 in the flange 5. These flanges engage the inner periphery of the shell as will appear.

Engaging the flanges 5 and 12 of both of the heads is the shell consisting of two similar members each comprising a semi-circular portion 13 having an inwardly extending flange 14 at each edge for engagement in the slots 6 and 11', the walls of said slots forming substantially radial shoulders or abutments for the flanges 14. The flanges 14 of the two semi-circular members 13 engage back to back in these slots and therefore form a means of transmitting the torque of the inner beam or drum structure to the shell. Intermediate the heads just described are suitable webs each comprising a disk 15 having a squared central opening 16 with oppositely extending slots 17, such openings receiving the inner shell or hub structure. Each of these webs is provided with a peripheral flange 18 and with diametrically opposed slots 19 extending through the flange 18 and inwardly through the web so as to receive the shell flanges 14. The semi-circular

shell portions are held in place with respect to the heads and intermediate webs by suitable rivets placed at convenient points and extending through the several parts.

5. The inner shell or hub structure is square in cross section as described and receives a square shaft. The tubular arrangement of this inner shell permits the easy threading of the shaft through the beam or drum. In 10 operation the drum is coated with rubber or other adhesive material and the fabric is placed in contact therewith and readily adheres to it. The fabric is then rolled on to the drum and the drum and fabric are placed 15 on a square shaft in a machine utilized in the industry. The fabric is drawn from the drum from time to time and the strain or drag exerted upon the shaft, to prevent reeling off and to hold the fabric taut, creates 20 a great strain upon the connections between the shell and the inner structure, this strain being transmitted in the present structure through the flanges of the shell to the heads and intermediate webs and to the shaft.

25 Having described my invention, I claim:

1. A beam or drum, comprising an inner member having substantially radial abutments for transmitting torque, an outer shell member, and integral shell portions coöperating with said abutments for transmitting the torque of one of said members to the other.

2. In a beam or drum, an inner hub structure, heads carried thereby and having substantially radial shoulders forming abutments, and an outer shell having integral portions engaging said shoulders whereby the torque of the shell is transmitted to the heads.

30 3. In a beam or drum, suitable heads, radially disposed shoulders near the periphery

of said heads, and an outer shell having inwardly extending flanges engaging said shoulders.

4. In a beam or drum, suitable heads each 45 having a radially disposed slot, and a shell having inwardly extending flanges engaging in said slots.

5. In a beam or drum, suitable heads therefor each having a plurality of radially 50 disposed slots extending out through the periphery, and shell members each having longitudinal flanges nesting in said slots.

6. In a beam or drum, a head having a cylindrical flange having radial slots extending 55 through the flange and into the head, and shell members having flanges nesting in said slots.

7. In a beam or drum, a pair of heads each comprising a main head portion having a 60 centrally disposed rectangular opening with radially extending opposed slots, a peripheral cylindrical flange with inwardly extending slots, a guide cone extending from said main head portion and having a peripheral 65 flange with inwardly extending slots in alignment with the slots of the main head portion, an inner hub shell comprising angular portions having nesting flanges engaging into the radially disposed slots at the center 70 of the main hub portion, semi-circular shell members secured to the heads and having flanges extending into the outer peripheral slots of the head members, intermediate webs between the heads comprising diaphragms 75 having suitable openings fitting and receiving the inner hub shell and slots for receiving the flanges of the shell, and means for holding the heads and webs against endwise movement with respect to the shell.

80 In testimony whereof I affix my signature.

ROBERT W. CORNWALL.
